Primary Examiner — Paula Greene(74) *Attorney, Agent, or Firm* — George A. Leone; Citadel Patent Law**CLAIM**

The ornamental design for a woodturning handle, as shown and described.

DESCRIPTION

FIG. 1 is a perspective view of a woodturning handle showing our new design;

FIG. 2 is a bottom side elevational view thereof;

FIG. 3 is a front side elevational view thereof;

FIG. 4 is a back side elevational view thereof;

FIG. 5 is a top side elevational view thereof;

FIG. 6 is a perspective view from the front side thereof; and, FIG. 7 is a perspective view of an alternate embodiment thereof.
